[57] **CLAIM**

The ornamental design for draft prevention flap for a sleeping bag, as shown and described.

DESCRIPTION

FIG. 1 is a right side elevational view of a draft prevention flap for a sleeping bag showing my new design, the left side being a mirror image thereof;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a perspective view thereof shown in use; the broken lines showing a sleeping bag being for illustrative purposes only and forming no part of the claimed design.
